UNITED STATES PATENT OFFICE.

JOHN BERGSTEN, OF NEW YORK, N. Y.

INSOLE.

1,334,213.

Specification of Letters Patent. Patented Mar. 16, 1920.

Application filed January 25, 1919. Serial No. 273,051.

To all whom it may concern:

Be it known that I, JOHN BERGSTEN, a subject of the King of Sweden, and a resident of the city of New York, borough of the Bronx, in the county of Bronx and State of New York, have invented a new and Improved Insole, of which the following is a full, clear, and exact description.

The object of the invention is to provide a new and improved insole to be inserted in shoes, boots and other footwear, and arranged to keep the feet of the user of the footwear warm and dry. Another object is to provide an insole which is naturally resilient thus insuring easy walking. Another object is to utilize the heretofore wasted bark of the balsa tree in the formation of the insole.

With these and other objects in view the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the insole, partly finished;

Fig. 2 is a similar view of the same in finished condition; and

Fig. 3 is an edge view of the same.

The insole is preferably manufactured from the bark of the balsa (*Ochroma Lagopus*), now generally wasted, the bark being exceedingly light, soft and porous and, therefore, exceptionally desirable for use as an insole. The front portion 11 of this body 40 is preferably split to permit the insertion of reinforcing sheets 12 of the same material but with the fibers running transversely, as plainly indicated in Fig. 1, these sheets being preferably arranged in a single layer side by side, with their meeting edges 14 extending transversely of the insole at a point approximately beneath the ball of the foot. A transverse break is thus provided in the insole at the point of greatest bend when walking, thereby providing the necessary

pliability for the insole. The heel portion 15 of the body is likewise split for the reception of a plurality of superimposed sheets 16 of the same material and with the fibers running transversely, as shown in Fig. 1. The several sheets are fastened together by stitches 20, sundry of which extend along the margin of the insole and others extend across and diagonally or in any other desirable manner, securely to fasten the layers together. It will be noticed that by the insertion of the sheets 12 the front portion of the insole is reinforced without being rendered unduly thick, and the heel portion is reinforced by the superimposed sheets 16, which, besides reinforcing the heel portion, provide the desired cushioning effect.

It is understood that in order to render the bark of the balsa serviceable for forming the insole it is necessary that such bark is cured by steaming the same to allow of removing the tough outer skin and to permit of readily splitting a sheet of a desired thickness and for forming thinner sheets for the insertion at the split front and heel portion of the main sheet.

It is understood that an insole made of the material mentioned and constructed in the manner described is exceedingly light and tends to keep the foot of the user of the footwear warm and dry.

Having thus described my invention, I claim as new and desire to secure by Letters Patent:

1. As an article of manufacture, an insole comprising a body sheet of fibrous material and having a plurality of layers with the fibers extending lengthwise of the insole, and reinforcing sheets of fibrous material interposed between the layers of the said fibrous body sheet at the front thereof, said reinforcing sheets arranged side by side in a single layer with their meeting edges extending transversely of said insole at the ball of the foot, reinforcing sheets of fibrous material arranged in a plurality of layers interposed between the layers of the said fibrous body sheet at the heel thereof, said front and heel reinforcing sheets having their fibers extending transversely of the

insole, and means for fastening said body sheet and reinforcing sheets together.

2. As an article of manufacture, an insole comprising a body sheet of fibrous material and having a plurality of layers with the fibers extending lengthwise of the insole, and reinforcing sheets of fibrous material with

the fibers extending transversely of the insole interposed between the layers of the said fibrous body sheet, said reinforcing sheets 10 arranged side by side in a single layer with their meeting edges extending transversely of said insole at the ball of the foot.

JOHN BERGSTEN.
